UNITED STATES PATENT OFFICE.

PETER H. KEIM, OF DIXON, ILLINOIS.

BELT-STRETCHER.

SPECIFICATION forming part of Letters Patent No. 251,892, dated January 3, 1882.

Application filed November 21, 1881. (No model.)

To all whom it may concern:

Be it known that I, PETER H. KEIM, a citizen of the United States, residing at Dixon, in the county of Lee and State of Illinois, have 5 invented certain new and useful Improvements in Belt-Stretchers, of which the following is a specification, reference being had therein to the accompanying drawings.

My invention relates to belt-stretchers; and 10 it consists in the construction, arrangement, and operation of its various parts, the details of which will be hereinafter more fully set forth.

In the drawings, Figure 1 is a top plan view 15 of my device; and Fig. 2 is a side view, showing cross-sections upon the lines $x x$ and $y y$, Fig. 1.

A A are the belt-keepers. Upon both ends 20 are downwardly-projecting blocks or lugs, a , which have formed in their inner sides wedge-shaped grooves, in which slide the belt-wedges a' , as shown. The grooves narrow from the 25 inner side of the keepers outwardly, so that when the belt-wedges are inserted into them under the belt they will press it firmly against the keeper, as shown in Fig. 2. Upon the 30 outer sides of the downwardly-projecting lugs a are formed the pulley-blocks a^2 , in which are pivoted the pulleys a^3 , as shown. Passing around these pulleys are the ropes B B, which 35 have their ends secured to the windlass C, as shown. At both ends of the windlass are levers $c c$, by which it is operated. Located centrally on the windlass is a ratchet, c' , and journaled on the windlass on each side of the ratchet is a pawl, c^2 , depending from which is an arm or lever, c^3 , as shown.

In the operation of the device the ends D 40 of the belt are passed into the keepers from their outer sides. The wedges $a' a'$ are then

placed into the wedge-shaped grooves of the 40 lugs a and pressed firmly into them against the belt, which prevents it from slipping. The windlass is then turned by the levers c^3 , which winds up the ropes B B, thus drawing the 45 keepers together and stretching the belt. The pawl c^2 engages with the ratchet c' , and the end of the arm c^3 bears against the belt, which 50 prevents it from unwinding. The separate ends of the belt may then be placed together, after which the stretcher may be removed by drawing out the wedges and lifting the device from the belt.

What I claim is—

1. The belt-keepers A A, upon both ends of which are downwardly-projecting blocks or 55 lugs a , which have upon their inner sides wedge-shaped grooves, in which slide the belt-wedges a' , adapted to hold the keepers firmly to the belt without slipping, said keepers being further provided upon the outer sides of 60 the lugs a with pulley-blocks a^2 , in which are journaled pulleys a^3 , all arranged to operate substantially as and for the purposes specified.

2. The keepers A and their pulleys a^3 , in combination with the ropes B and windlass 65 C, all arranged to operate as described.

3. The windlass C, provided with a ratchet, c' , pawl c^2 , lever c^3 , and ropes B, operating in combination with the keepers A A and their attachments substantially as and for the purposes specified.

In testimony whereof I affix my signature in presence of two witnesses.

PETER H. KEIM.
